Application December 8, 1942, Serial No. 468,182

4 Claims.

(Cl. 89—1)

This invention relates to ordnance and more particularly to a novel and useful gun of the muzzle-loading mortar type.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Fig. 1 is a side elevation of a gun and mounting embodying the invention;

Fig. 2 is a front elevation of the same;

Fig. 3 is an enlarged fragmentary vertical section on line 3—3 of Fig. 1;

Fig. 4 is a fragmentary sectional detail on line 4—4 of Fig. 2, showing the base portion in elevation;

Fig. 5 is an enlarged fragmentary sectional detail of the breech end of one of the gun barrels;

Fig. 6 is an elevation, with parts in section, of a projectile to be fired in the gun; and

Fig. 7 is a fragmentary, partly diagrammatic section, with parts in elevation, of a modification of the invention.

Objects of the invention are to provide a new and improved muzzle-loading mortar-type gun, wherein the possible rate of fire is very greatly increased over known types of muzzle-loading mortars and wherein said improved muzzle-loading gun is designed and adapted for very rapid and accurate traversing and elevating and depressing through a great vertical angle, whereby it is capable of use in anti-aircraft operations, particularly against low-flying planes on dive-bombing and ground attack missions. By virtue of the invention it is possible to provide a very rapid firing weapon capable of delivering high explosive, time-fuse-controlled, fragmentation-type projectiles of large caliber and capacity at any angle of site from near the horizontal to the complete vertical.

The present invention is an improvement on that disclosed and claimed in the co-pending application of Clare H. Armstrong and Alexander J. Stuart, Jr., Serial No. 443,378, filed May 18, 1942.

One important feature of the invention is the

provision of means for releasing air and other gases from the breech of the gun except during the firing of a round. By means of automatically-operated valve mechanism, I provide that air and gas may escape from the breech of the gun except when the projectile is seated therein and thereafter until the projectile has been propelled from the muzzle by the propellant gases. This feature of the invention has many advantages as hereinafter set forth. Primarily it increases the speed of loading by eliminating resistance to fall of the projectile toward the breech occasioned by the entrapment of air and building up of counter-air pressure; it enables loading at very much lower angles of site than now possible; it removes the difficulty of centering the projectile to strike the firing pin with the percussion cap; eliminates fluttering of the projectile falling through the barrel; and also permits the use of a much closer fitting projectile, thereby increasing the potential muzzle velocity and effective range of the weapon.

The present invention provides further improvements in the relationship between said valve mechanism and the firing pin whereby it is assured that firing cannot take place until the valve is securely seated, thus preventing escape of gas between the valve and its seat with consequent loss of muzzle velocity. This feature of my invention also increases the safety of use of the gun by making it possible to withdraw the firing pin and/or valve mechanism or back same away from a projectile seated in the breech of the mortar in the event of a misfire or a broken pin so that danger of handling a misfired projectile is largely reduced.

All of these advantages of the invention are combined with great simplicity of construction for gun, mount and ammunition, simplicity of operation and maintenance; and exceedingly low cost of construction. As to the latter no rifling of the barrels is required; no expensive breech mechanism, and no fire control mechanism which is usually very expensive and delicate. The weapon also is quite light in weight so that it may easily be transported and be fired from a truck or other vehicle.

It will be understood that the foregoing general description and the following detailed description as well are exemplary and explanatory but are not restrictive of the invention. Referring now in detail to the present preferred embodiment of the invention, illustrated by way of example in the accompanying drawings, the invention is shown in connection with a mount-

ing for one or more muzzle-loading gun or mortar barrels whereby same may be traversed through 360°, elevated to the vertical and depressed to a very low angle. These movements are imparted to the gun barrel or barrels by a single operator who is positioned so as to remain in fixed relation to the axis of the barrels at all times. As shown, a barrel 10 having a smooth tubular bore is seated at its lower or breech end 11 in a receiver block 12 having a cylindrical, threaded interior which has threaded engagement with the externally-threaded portion 13 at the breech end of the barrel. The muzzle end of the bore is slightly chamfered at 14 to facilitate introduction of the projectile. In general the construction of said barrel is similar to that used in the Stokes infantry mortar.

The receiver mechanism is designed to accommodate two such barrels mounted and fixed in parallel relation as shown in Fig. 2 or, if desired, a single such barrel may be centrally positioned on the mounting. For this purpose three receiver blocks 12 are provided, each of said blocks being formed with a flat flanged backing 15. The backing portions 15 of the receiver blocks are each bolted to the underface of a flat mounting plate 18 and are equally spaced across the face thereof. As shown in Fig. 2, the two flanking receivers 12a and 12b are provided with barrels 10a and 10b respectively while the central receiver 12c is idle, but it will be understood that a single barrel of identical form may be mounted in the receiver block 12c and the twin barrels on either side omitted. Additional support for axial thrust along the barrels is provided by a pair of ribs 17 and 19 which are welded to an underface of the plate 18 and project at right angles therefrom to underlie the bottom face of the receiver block 12. As shown in Fig. 2 there is a pair of said ribs 17 and 19 so positioned with respect to each of the receiver blocks 12a, 12b and 12c.

The embodied means for providing angular variable support for the gun barrels, as previously stated, comprises a flat circular rotatable platform 20 on which the receiver plate 18 and the attached receivers and barrels are mounted for horizontal rotation or traversing movement with the platform and with respect to which they are angularly movable in vertical planes. Referring first to the mounting for permitting vertical planar or elevating and depressing movement of the barrels, the lower portion of plate 18 is provided with a pivot block 25 fixed to and projecting at right angles downwardly at the bottom face of said plate 18. Said pivot block 25 is provided with a horizontal bore 26 for rotary support on a horizontal pintle or hinge pin 27. Said hinge pin extends from either side of the block 25 and the extending ends thereof are journaled in suitable journal blocks 28. Said journal blocks are integrally fixed to a base plate 29 which in turn is bolted to a thrust plate 30 which lies upon and is fixed to the upper surface of the platform 20 at the center thereof. An upstanding lip 31 is formed in said thrust plate to contact with the rear edge of plate 29 and thereby to secure same from the horizontal component of the recoil of the gun.

The embodied means for permitting horizontal rotation or traversing movement of base platform 20 comprises primarily a ball bearing at the circular periphery of said plate. The plate 20 is provided with a downwardly-disposed vertical flange 35 at its periphery. An upper race-

way 36 for the ball bearing is fixed in the angle formed between said flange and the under surface of the plate. The lower raceway 37 is similarly fixed to the upper surface of a stationary base plate 38 which underlies and is substantially co-extensive with the plate 20. A horizontally-projecting guard lip 39 may extend at the periphery of said plate 38. Balls 40 are mounted between the upper and lower raceways and are held in position by the usual cage 41. A dust seal or gasket 42 may be formed between the periphery of the lower race and the inner face of flange 35.

Additional vertical rotational support is provided at the center of platform 20 for said platform and the parts attached thereto. As embodied, a horizontal reinforcing plate 45 is seated on and fixed to the upper surface of base plate 38 centrally thereof. A central vertical post 46 is reduced and threaded at its bottom end 47 and thus seated in an appropriate threaded opening at the center of the superposed plates 45 and 38. A self-aligning ball bearing is mounted on said plates 45 and 38 and about said post 46, said ball bearing being positioned and designed to provide the central support for the platform 20 as previously stated. Said ball bearing comprises an aligning washer 48 mounted on reinforcing plate 45 by an intervening flat washer 49. The lower race of the ball bearing comprises the annular member 50, the lower surface of which is spherically-shaped to rest upon the conforming upper face of washer 48. The upper ball race of the bearing comprises the annular member 51 which also surrounds the post 46 and rests upon the balls 52 of the bearing. The ball bearing assembly above-described is housed within a cup-shaped casing 55 which is fixed to and depends from the undersurface of the platform 20. An outer spaced annular wall 56 also depends from the under surface of said platform and surrounds the bearing assembly as will be clear from Fig. 3. Lateral thrust support for the central ball bearing assembly is provided by an upstanding annular wall 59 fixed to the upper surface of plate 45 and having rotary surface engagement with the depending portion of the cup 55. The post 46 extends upwardly through aperture in plate 30 and into a recess 57 in plate 29, the latter being shaped to loosely enclose the enlarged head 58 on the post.

Means are provided for imparting controlled traversing rotation to the platform 20, same preferably to be actuated manually and as designed is intended to provide very rapid rotary movement to the platform, its occupants and other equipment thereon while at the same time the amount of manual power required is very small. For this purpose the platform 20 is adapted to be rotated on its ball bearings by the driving action of a geared pinion 60. Said pinion meshes with teeth 61 formed on the annular flanged member 62 which is fixed to the periphery of the plate 45. Pinion 60 is at the lower end of stub shaft 65 which extends through a suitable aperture in the platform 20 and is journaled in a bracket 66 fixed to said platform. To the upper end of stub shaft 65 is keyed a bevel gear 67 which is meshed with beveled gear 68 on horizontal stub shaft 69, the latter being supported in the upstanding portion 70 of bracket 66. Sprocket wheel 71 is keyed to the hub of beveled gear 68 and is driven by sprocket chain 72.

The embodied means for imparting driving force to the above-described sprocket gearing for

traversing movement comprises a hand wheel 80 which is fixed to one end of horizontal shaft 81, on which is keyed a sprocket wheel 82 engaging the upper reaches of the vertically-looped chain 72. The shaft 81 is journaled in a vertical side bracket plate 85, the lower end of which is curved inwardly at 86 and there welded to the top surface of the plate 18. A suitable handle 87 projects inwardly from the face of the hand wheel 80 and is mounted near the periphery thereof.

The gearing ratio between the hand wheel 80 and the gearing 60—61 is such that very rapid rotation of the platform 20 and guns thereon may be effected by relatively easy turning movement of the hand wheel by the operator, while not limited to any specific ratio. In the preferred form the gearing ratio is such that one complete traverse of the platform 20 through 360° may be made in 10 seconds or less. Thus the traversing required for firing at an airplane crossing the gunner's front at 400 M. P. H. and a range as short as 600 yards (a most extreme condition) is well within the ability of a gunner of average dexterity and strength.

Referring now to the present preferred means for moving the gun or guns in the vertical plane to elevate and depress them, such angular motion is imparted to the gun-supporting plate 18 by means of a vertical bracket plate 90 which is substantially the same in construction as the opposite bracket plate 85 and is similarly curved at its bottom end 91 for fixed attachment to the top surface of plate 18. Angular motion is imparted to said bracket plate 90 by means of a hand wheel 93 connected to said plate by a horizontal shaft 94 which is journaled in a U-shaped yoke 95. The inner arm 96 of said yoke is fixed to the upper end of the plate bracket 90. Rotatably mounted on said shaft 94 between the arms of said bracket 95 is a pinion 97 which is geared to mesh with the gear teeth 98 of a segmental rack 99. Said rack is formed on the upper arcuate edge of a vertical plate 100, the bottom of which is secured to the upper surface of the platform 20. As will be clear from the drawings, rotation of hand wheel 93 by its inwardly projecting handle 101 causes the gear 97 to rotate in mesh with the rack and travel along the curved surface thereof and thereby to rock the plate 18 and the attached gun barrels and other parts about the horizontal axle or hinge pin 27. The arc covered by the rack 99 is slightly greater than 90° so that the gun may be elevated from the horizontal position of maximum depression to the maximum elevation of complete vertical.

In the present preferred form the gear ratio for elevating and depressing motion is such that the entire arc from vertical to horizontal can be accomplished in about four seconds, with ten turns of the hand wheel, but it will be understood that this is not limiting of the invention as previously explained.

Means are provided for positioning the gunner or operator controlling the traversing and vertical movements of the gun or guns so that both hand wheels 80 and 93 may be simultaneously operated by the single gunner using both his hands while the gunner is seated in fixed relation to the axis of the barrel or barrels 10 regardless of what their angular position may be either vertically or in azimuth. This feature of the weapon also is designed to place the gunner automatically in position at all times so that his line of sight is always parallel to the angle of site of the barrels. As embodied, the upper surface of the re-

ceiver-supporting plate 18 is made the seat of a chair for the gunner as shown diagrammatically in Fig. 1. An elongated and suitable curved back plate 105 is attached to the rear edge of said seat plate 18 and projects at right angles thereto so as to form a back and head rest for the gunner. Suitable cushions C may be attached to the surfaces of the seat plate 18 and the curved back 105. By remaining seated in natural position on the seat 18 with his back and head against the conforming surface of the back plate 105, the gunner is automatically and comfortably positioned in a fixed relation to the barrels 10 so that no matter how the gunner is traversed, elevated or depressed, he will always be seated in exactly that same relative position. If the gun is elevated to a full 90°, the rear of the backrest 105 will come in contact with the upper surface of the platform 120 where the gunner reclines without discomfort and with no change in his relative position with respect to the barrels.

To facilitate ease of vertical angular movement in all positions, equilibrating springs may be provided between the barrels and the platform. As shown (Figs. 1 and 4), one end of a helical spring 200 is pivotally fixed to platform 20 by a tubular casing 201 which is hinged at its bottom to a lug 202 on the platform by a hinge pin 203. The upper end of the spring is similarly fixed to the end of a telescoping tube 204 which is pivotally connected to plate 18 by lug 205 and pin 206. Thus the spring and telescoping casing act to balance the weight of the gunner as he tilts back and thus to ease the depression of barrels.

For greater convenience and security the gunner is preferably provided with foot supports or treadles 110 and 111 which are so positioned and connected to the remaining portion of the seat assembly as to further insure that the gunner will remain seated at all times in the right-angled position required. For this purpose each of the foot treadles is formed as the lower flange of a Z-shaped bracket having a right-angled riser portion 112 and a rearwardly inclined upper portion 113. The latter is rigidly attached to a depending member 114, the upper end of which is pivotally connected to lugs 115 on the under surface of the plate 18 by a pivot pin 116. Said foot support 111 thus normally hangs freely pivotally from the front edge of the seat plate 18, but is prevented from swinging below the angle shown in Fig. 1 by a stop member (not shown). When the barrel or barrels 10 are depressed below a certain angle, the edge 116 at the rear of the foot treadle 111 will come against the upper surface of the platform 20 and thereafter the pivotal motion will permit same to slide along said surface and thus allow the gunner's legs to straighten out in front of him as the barrels are further depressed and preferably a cleat 117 is provided on the treadle 111 for bracing the gunner's heel and side plate 118 may be provided for confining his foot laterally. It will be understood that the construction of the foot rest member 110 is identical with that described for treadle 111.

Sighting means are positioned in the line of sight of the gunner whereby he substantially automatically is constrained to look through said sight by virtue of his position in the gunner's seat.

As embodied a sighting tube 120 is shown rigidly mounted in front of the gunner and at the level of his eyes and axially parallel to the barrels 10. Said sighting device itself is indicated diagrammatically and not shown in detail as the invention is not confined to any particular form of

such means but any known form of rear area or forward area sight may be employed. The sighting tube 120 is positioned as stated by means of a curved bracket yoke 121, the lower ends of which are fixed to the upper ends of the side plate brackets 185 and 90 respectively. The sighting tube 120 is supported by a rod 121 which may be adjustably held in an aperture in the top of bracket 121 by means of a wing bolt 122 or other suitable means. The yoke 121 also serves as a transverse strengthening member for the superstructure of the traversing or elevating member. A suitable projectile for the gun is somewhat diagrammatically shown in Fig. 6. As shown, same varies little from the presently-used infantry Stokes mortar projectile and comprises a "tear drop" shaped explosive-containing shell 130 having bourreleto rings 131 at its maximum diameter. The lower or base end of the shell tapers to a cylindrical tail portion 132 to which is attached the propelling means. The latter comprises a plurality of radial vanes 133 of known construction having flanged edges 134 and intermediate fire propellant holding openings 135. Said vanes are attached to a cylindrical core 136 into which the igniting cartridge 137 is inserted. The latter is substantially like a shot gun shell in construction, having a slightly recessed base end 138 at the center of which is placed the conventional percussion cap 139. A plurality of openings 140 are provided in the wall of the core 136 for fire distribution. Increments of propellant 141 of conventional shape are shown positioned in the spaces between the vanes.

The nose end of the projectile is preferably provided with a time fuse 150. While the latter may be of several types I have found the conventional powder-train time fuse to be generally satisfactory. As is known, the times for this fuse may be set by hand simply by turning the fuse-setting ring 151 to the proper fuse setting as indicated by the graduations on said ring. Said fuse is bore safe, armed by set-back (i. e. by the initial impact of firing and not by rotation); such fuse also is self-destroying and preferably designed also to burst upon impact as well as the time set for any point on the trajectory. The 1907, 21 second powder-train fuse is one having most of these features and could be used substantially without change in connection with the present invention merely by providing a somewhat weaker spring in its forward element so that it will be armed by a lesser set-back impact.

It will be understood that the gun and mount hereinabove described are illustrative of one embodiment with which the improved features of the present invention may be utilized but, inasmuch as said invention relates primarily to the improved construction of the firing pin and valve mechanism, it will be understood that same is also applicable to other types of mounts for muzzle-loading gravity-operated mortars. For example, same may be used with the conventional Stokes type trench mortar as will be obvious without further description.

In accordance with the invention I provide improved means for increasing the speed of loading and firing the muzzle-loading barrels 10 by relieving the air pressure which normally builds up as the mortar projectile is dropped into the muzzle of the barrel. This feature of the invention is of great importance also because it permits loading at greatly reduced elevations because the speed of falling of the projectile into

the barrel is sufficient to fire the cap even at a very slight angle of fall because the retardant effect of air pressure in the barrel is eliminated. The projectile also falls much more smoothly without wobble or flutter as the rush of compressed air past the bourrelet is substantially eliminated. This in turn makes it possible to use a projectile which fits more closely into the bore of the barrel so that a greater effective propelling effect and muzzle velocity result. That is, the bourrelet ridges 131 may be machined to a closer fit relative to the bore, thus reducing escape of propellant gases past the sides of the projectile in the bore and thereby giving a greater initial propelling pressure. Another advantage of this feature of the invention is that residual gas in the breech end of the barrel from a previous firing is virtually eliminated as said gases escape from the breech end of the gun after the projectile has left the barrel. This is a very important factor in increasing the rate of fire and the safety thereof because in normal practice of firing Stokes mortars with a closed breech the collection of residual gases in the breech end was a serious handicap.

Referring now to the present preferred embodiment of means for so controlling the escape of air at the breech end of the barrel, such means are shown in detail in Fig. 5. As there shown the cylindrical threaded socket 160 of the receiver block 12 terminates in a shoulder 161 against which the bottom end 11 of the barrel is seated when same is screwed down to the limit. A second annular shoulder 162 of reduced diameter is formed slightly below said shoulder 161 and within that an annular arcuate groove 163 to provide clearance for the lower edge of the projectile fins. A central flat annular raised portion 164 lies within said groove 163 and constitutes a table within which a valve seat is formed to receive the valve head 165 when the latter is seated. A tapered or conical valve seat 166 is formed inside the table 164, said seat terminating in a cylindrical opening 167 which extends downwardly through the block 12 for a substantial distance. Transverse air and gas ports 168 communicate with the cylindrical opening 167 and lead therefrom to the outside of the block 12. There are preferably at least four of said ports provided. Additional communications therefrom to the atmosphere are also provided by vertical conduits 169 which lead to the bottoms of said ports 168.

Means are provided for holding open the valve seat and cylinder 167 and the exhaust ports as described during all times when the gun is idle and except when the projectile is being fired. Accordingly, the valve head 165 has a flat upper face 170 which as previously stated is adapted to lie flush with the table surface 164 when the valve is closed. A conical portion 171 lies below said upper surface 170 and is shaped to fit exactly into and against the seat 166 when the valve is closed. The valve head therebelow is reduced to an elongated tubular stem portion 172 which is considerably less than the diameter of the interior diameter of the cylindrical opening 167. The lower end of said valve stem is threaded at 173 and is there engaged by the threaded interior of a cup-shaped nut 174 and an intervening threaded washer 175 which abuts against the bottom face 176 of the receiver block 12. The lower face of said cup-shaped nut 174 provides a seat for the upper end of helical expansion spring 177 which surrounds the lower part 173 of the valve stem and

extends downwardly therefrom so that its lower end rests against the bottom of a hollow cup-like member 190 fixed to the lower end of the firing pin 180 which projects upwardly through the bore of the valve stem. These parts are enclosed in a cup-like housing 178, the upper end of which is interiorly threaded at 179 to engage the correspondingly threaded and reduced projection portion 176 of the receiver block 12. Said spring 177 is quite weak and tends to hold the valve head 165 in the open position only when no substantial force is exerted to close same, while constantly urging the lower end of the firing pin against the bottom of housing 178.

In operation the descending projectile, which falls with its butt toward the breech of the barrel, first strikes the elevated valve head surface 170 and pushes same to the closed position against the spring. Upon subsequent firing of the projectile expanding propellant gases in the breech chamber between the bourrelet rings of the projectile and the receiver block at the breech maintain the valve closed until the projectile has cleared the muzzle of the piece. Thereupon the escape of the gas immediately permits the spring 177 to raise 25 the valve and thus permit the accumulated gas to escape rapidly from the breech end of the barrel as well as the muzzle.

Means are provided for causing the projectile to be fired as soon as it reaches the bottom of the barrel and the valve head 165 is in closed position, but no earlier. For this purpose the firing pin 180 is positioned to strike the percussion cap 139 of the projectile only when the latter has fully descended into the breech and closed or virtually closed the valve.

The lower end of the firing pin is fixed relative to the valve stem by the downward pressure of spring 177 against the enlarged end portion 190 of the pin which is engaged by and seated against a threaded adjusting number 185 in the threaded bore 186 in the lower end portion of the cup member 178. The threaded end of the adjusting member 185 projects beyond the bottom surface of said cup member and is there engaged and held by a check nut 187. By means of this construction, it will be clear that the firing pin is firmly held in position but may be advanced or retracted with respect to the bottom of the barrel so as to provide more or less projection thereof for firing operations. By turning of the nut 187 on the threaded portion 173 of the valve stem exactly the desired relation between the projecting end 182 of the firing pin and the setting of the valve may be arrived at by experiment, while it is also possible by such means to back off and entirely withdraw the firing pin, if need be, as in the case of a misfire.

The operation of the invention will be generally understood from the foregoing description. The gunner, from his seat, operates the elevating hand wheel with his right hand and the traversing hand wheel with his left. He continuously observes the field of fire through and around the sight from his fixed position in the seat. By practice and observation he quickly learns how to operate the hand wheels so as to apply the proper lateral lead or deviation and the proper vertical angle for elevation and super-elevation. He also can estimate the fuse settings for the changing ranges of the moving target and will call out such settings to the crew so that the proper fuse for the next shot will be cut and the round loaded into the muzzle. In practice a plurality of fuses of graduated times of flight will be cut in advance

so that the gunner will merely call for them in the desired order.

An operator for loading the muzzle of a gun will stand on the platform 20 so that he can reach the muzzle of the adjacent barrel and drop a projectile therein, butt end lowermost. As soon as that projectile has fired, he will drop another with the fuse range as called for by the gunner and so on. With the invention loading and firing speeds of the order of fifty rounds per minute per barrel are quite possible. When twin barrels are provided two loaders will stand on the platform, one adjacent either barrel, and each will operate as described, under the single directional commands of the gunner. The loading operation is of extreme simplicity due to loading from the muzzle. As contrasted with breech-loading guns, loading is easier at elevated angles in the neighborhood of the vertical than it is at lower elevations such as thirty degrees. Moreover, the "contour" of the gun exposed to view is relatively very small because the breech may be kept very low, only separated from the ground by the thickness of traversing platform.

The great simplicity of the gun makes it cheaply producible in large quantities, while the small pressures and weights involved require no critical or strategic materials.

A modification of the invention is shown in Fig. 7, wherein is disclosed the principle of utilizing a vacuum or low-pressure source for facilitating the fall of the projectile against the firing pin by venting the gaseous pressure between the breech end of the barrel and the falling projectile 35 more rapidly than same would escape to the atmosphere through the valve ports provided as hereinabove described. As somewhat diagrammatically shown in Fig. 7, the valve and firing pin construction previously disclosed is provided with 40 one or more gas-escape ports 168 which, instead of leading to the atmosphere, are connected to suitably arranged conduits 200 which lead to a source of low pressure such as the intake side 201 of a vacuum pump 202 or the like. Said pump 45 may be operated by a suitable motor 203 or, if desired, may be actuated by other power means such as may be derived from the recoil of the firing, the rotation of the gun mount or the like. It will be understood that such low pressure attachment will increase pro tanto the rapidity of 50 fall of the projectile and the scouring of accumulated gases after firing.

The invention in its broader aspects is not limited to the specific mechanisms shown and described but departures may be made therefrom within the scope of the accompanying claims without departing from the principles of the invention and without sacrificing its chief advantages.

60. What I claim is:

1. In a gun in combination a barrel having an open muzzle for receiving a projectile insertible at said muzzle and movable along the bore of the barrel toward the breech end thereof, a firing pin seated at the breech end of the barrel and adapted to be struck by the moving projectile when same reaches the breech end of the barrel, valve means normally lying in the path of the falling projectile between same and the firing pin, said valve means being moved to close by the falling movement of the projectile whereby said valve is closed by the time the projectile comes into contact with the firing pin.

2. In a gun in combination a barrel having an 75 open muzzle for receiving a projectile insertible at

said muzzle and movable along the bore of the barrel toward the breech end thereof, a firing pin seated at the breech end of the barrel and projecting thereabove sufficiently to contact the percussion cap of the projectile when same has fallen to the bottom of the barrel, a gas escape port at the bottom of the barrel, a valve normally held away from said port but movable to close same upon contact with the falling projectile, said valve in its open position lying between the contact end of the firing pin and the falling projectile and, in its closed position, being below said projecting end of the firing pin.

3. In a gun in combination a barrel having an open muzzle for receiving a projectile insertible at said muzzle and movable along the bore of the barrel toward the breech end thereof, a firing pin seated at said breech end of the barrel and projecting a short distance into said barrel,

a valve movable axially with respect to the barrel and the firing pin at the breech end of the barrel, and a valve port at said end adapted to be closed by said valve, means for normally holding said valve open and in a position axially beyond the end of the firing pin, said valve being movable by force exerted axially toward the breech end of the barrel to close the port and thereby to expose the end of the firing pin.

- 10 4. In a muzzle-loading gun in combination a firing pin seated in the breech end of said gun and projecting upwardly therefrom toward the muzzle of the barrel, a tubular valve member slidably mounted for axial movement on said pin, 15 a gas port in the breech adapted to be closed by said valve, means for holding said valve open and above the upper end of the firing pin.
